UNITED STATES PATENT OFFICE.

GUSTAVUS A. SCHLECHTER, OF READING, PENNSYLVANIA.

DESIGN FOR A BADGE.

SPECIFICATION forming part of Design No. 21,866, dated September 27, 1892.

Application filed June 29, 1892. Serial No. 438,449. Term of patent 3½ years.

To all whom it may concern:

Be it known that I, GUSTAVUS A. SCHLECHTER, a citizen of the United States, residing at Reading, in the county of Berks, State of Pennsylvania, have invented a certain new and original Design for Badges, of which the following is a specification.

The leading feature of my design consists in the representation of an old-fashioned high hat with the head and tail of an animal projecting from the interior through the cover and below the rim and reeds stuck in the hat-band, as shown in the drawing, where said representations appear in relief upon the field of a circular body having a marginal bead.

The crown of the hat is represented as broken, so as to form a considerable opening, through which the head of a coon, whose body

is mainly concealed by the body of the hat, projects, while the end of the tail extends below the hat-brim. The ends of the reeds are engaged by the hat-band, and they extend diagonally upward in front of the hat.

I do not claim as my invention the mere representation of a hat, the novel appearance of my design being due to the additional features shown and described.

What I claim is—

The design for a badge or similar article, substantially as herein shown and described.

In testimony whereof I affix my signature in presence of two witnesses.

GUSTAVUS A. SCHLECHTER.

Witnesses:

JACOB UMSTEAD,
DANIEL ERMENTROUT.
